UNITED STATES PATENT OFFICE

ALBERT E. GRANT, OF NEW YORK, N. Y., ASSIGNOR TO CALOROIL BURNER CORPORATION, A CORPORATION OF DELAWARE

OIL BURNER

Original application filed May 2, 1921, Serial No. 466,183. Divided and this application filed May 14, 1927. Serial No. 191,337.

This invention relates to oil burners and particularly to the nozzle devices of such burners, the general object of the invention being to provide nozzle devices of a new and improved construction and arrangement whereby they are rendered clean and free of oil automatically.

To the above and other ends which will hereinafter appear, the invention consists in features of construction, combinations of devices, and arrangements of parts hereinafter described and particularly pointed out in the appended claims.

The invention will be described in detail in connection with the accompanying drawings wherein

Fig. 1 is an elevation of the nozzle device;
Fig. 2 plan view thereof;

Fig. 3 is a longitudinal vertical sectional view and

Fig. 4 an end elevation looking from the left in Fig. 1.

The present case is a division of my prior application, Serial No. 466,183, filed May 2, 1921, which has eventuated in Patent 1,632,402 granted June 14, 1927.

The present invention was particularly designed for use with oil burner apparatus of the type disclosed in said patent, but it is to be understood that this invention is not restricted to such use. The nozzle devices are of the jet operated type, and while steam is used as an atomizing medium any other suitable medium such as air under pressure may be employed; and it is also a matter of choice whether the fuel supply means supplies fuel by gravity or pumps it under pressure or otherwise maintains it at a constant level to be aspirated.

The flame-forming nozzle herein shown comprises essentially a steam nozzle such as 23 having a passage 43 directed for instance horizontally and an oil pipe 44 inclined preferably about 45° in the direction of the jet and having an oil passage 45. The end of the oil pipe 44 is positioned in the path of the steam jet and is slightly inclined downward with relation to the axis of this jet so that the passage opens in the direction of the jet. The edge 46 of the oil pipe 44 is

preferably made thin with the surrounding surfaces rounded off slightly as by rubbing with emery in order to prevent the edge from being split by the impinging steam or other fluid as would be the tendency if the edge were left sharp as cut. The rear point 50 of the edge 46 is slightly higher than the front point or lip 51, as indicated by the angle α in Fig. 1 wherein the deflection of the top edge toward the left has been exaggerated for the sake of clearness. The steam jet striking along the back surface 52 is deflected upward and outward sweeping around the edge 46 on smooth lines and merging finally with the other jet lines. The result is not only the creation of a vacuum but a drawing of the steam particles along the edge 46 keeping it clean and free from any accumulation of thickened oil. The point 50 is preferably positioned in the jet above the center line of the opening 43 and for the structure shown in the drawings it has been found that the most efficient action is obtained with point 51 at a distance of nearly one third of the radius of passage 43 above the center.

The distance between the nozzle 23 and oil pipe 44 along the axis of the jet will depend upon the particular results desired and upon the steam pressure and the size of the orifice 43. In the example shown in the drawings the point 50 is spaced from the end of the nozzle about three times the diameter of the nozzle passage 43. In the flame forming nozzle of this invention the diameter of the oil duct or passage 45 is very large and the oil is sucked therethrough from a lower constant level so that a constant resistance is imposed on the oil feed due to the distance the oil has to be raised to reach the edge 46. In the nozzle 23 with a steam orifice 43 of one eighth of an inch and relatively low steam pressure of less than twenty pounds per square inch the oil passage 45 may be one quarter of an inch in diameter. This large oil passage and high suction and direct action of the steam on the edge 46 provide a flame forming nozzle that not only efficiently draws up and vaporizes and mixes the oil but also avoids all stoppage or stuffing of the oil pas-

sages. The steam stream surrounds the oil which does not come into contact with the air until at some distance from the nozzle so that the flame never approaches the oil in liquid form and the temperature of the oil passage at the edge 46 is constantly that of the steam.

Relative adjustment of the steam and oil passages may be provided as by nuts 65 threaded on the nozzle stem 66 and by worm-wheel nut 67 threaded on the stem 68 of the oil pipe. The threaded stem 68 passes freely upward through an opening indicated at 68a in Fig. 3 which is of greater diameter than the stem itself so that up-and-down movements under control of the worm wheel 67 are not interfered with. The worm wheel 67 is turned by worm 69 on rod 70 and this adjustment automatically locks the parts at each setting. All the parts may be mounted in a single frame 71.

It will be understood that the source of oil supply has its level considerably below the top of the nozzle 44 so that normally the level of the oil in the nozzle is below the top and after operation will always drop back to the normal level.

It will be observed that by the present invention there is provided a highly efficient nozzle device, the parts of which are readily adjustable to obtain the best results.

Various changes may be made without departing from the spirit and scope of the invention.

26 I claim:

1. In an oil burner the combination with a jet forming orifice, of means for supplying oil to said jet comprising a tube inclined in the direction of said jet and having its end cut diagonally with relation to the axis of said tube and in a plane coinciding approximately with the direction of the axis of said orifice and inclined slightly forward with relation thereto, so that said oil tube opens away from said orifice and in the direction of said jet, and the jet striking against the back surface of said tube and deflecting upward and outward sweeps around the edges of the oil tube opening on smooth lines to draw the jet particles along said edge and prevent dripping of the oil therefrom.

2. In an oil burner the combination with a jet forming orifice, of means for supplying oil to said jet comprising a tube inclined in the direction of said jet and having its end cut diagonally with relation to the axis of said tube and in a plane coinciding approximately with the direction of the axis of said orifice and inclined slightly forward with relation thereto, so that said oil tube opens away from said orifice and in the direction of said jet, and the jet striking against the back surface of said tube and deflecting upward and outward sweeps around the edges of the oil tube opening on smooth lines to draw the jet

particles along said edge and prevent dripping of the oil therefrom, said oil tube being adjustable with relation to said orifice by rectilinear movement at right angles to the axis of said orifice so that the end of the oil tube may be moved directly across the jet without changing its angular relation thereto.

3. In an oil burner the combination with a jet forming orifice, of means for supplying oil to said jet comprising a thin wall tube extending upward into said jet and having its upper discharge end in substantially the plane of the axis of said jet and formed as an elongated opening of greater length than width and with its longer axis extending in the direction of said jet, so that the jet sweeps around the edges of the oil tube opening on smooth lines to draw the jet particles along said edge and prevent dripping of the oil therefrom, said oil tube being adjustable at right angles to the axis of said jet, so that the end of the tube is movable along rectilinear lines across said jet in front of said orifice.
